UNITED STATES PATENT OFFICE

90,445

DESIGN FOR A STORE FRONT

Hugh J. McNeil, Reading, Mass.

Application May 6, 1933. Serial No. 48,027

Term of patent 3½ years

To all whom it may concern:

Be it known that I, HUGH J. MCNEIL, a citizen of the United States, residing at Reading, in the county of Middlesex and State of Massachusetts, have invented a new, original, and ornamental Design for a Store Front, of which the following is a specification, reference being had to the accompanying drawing, forming a part thereof.

Figure 1 is a plan view

Fig. 2 is a front elevation of the store front showing my new design.

I claim:

The ornamental design for a store front substantially as shown.

Signed at Boston, in the county of Suffolk and State of Massachusetts, this 4th day of April, 1933.

HUGH J. MCNEIL.
